MANUFACTURE OF SHOES AND
SHOE SOLES

Alfred E. C. Hall, Webster Groves, Mo., assignor
to United Shoe Machinery Corporation, Pater-
son, N. J., a corporation of New Jersey

Application December 13, 1934, Serial No. 757,363

11 Claims. (Cl. 12—142)

This invention relates to improvements in methods of making shoes and to improvements in shoes and shoe soles as articles of manufacture. In preparing an outsole for direct attachment to a shoe by means of through-and-through stitching it is customary to form a channel and a channel flap along the marginal portion at the tread face side of the sole and subsequently to raise the flap thereby opening the channel to facilitate the reception of the stitches therein. After the sole has been stitched to the shoe the raised channel flap is laid to cover the stitches. While this practice is effective for the purpose of covering and protecting the stitches, the stitches form a ridge in the channel which is liable to produce a corresponding ridge in the outer surface of the channel flap, thus detracting from the finished appearance of the shoe bottom. Such a ridge in the channel flap may be flattened out by rubbing or sanding operations, but the latter frequently result in mutilating more or less the surface of the sole and in that way detracting from its appearance in the finished shoe. In some cases a shallow stitch-receiving groove is formed in the channel into which the stitches are laid flush with the inner side of the channel but in such instances depressions are liable to be formed in the material of the channel flap where the latter is forced into the spaces between the stitches by the flap laying or leveling pressures.

One object of the present invention is to overcome the above-mentioned undesirable conditions in the manufacture of shoes of the above-mentioned and other types and to insure that the outsole-attaching stitches shall be concealed in such a manner that their presence will not be discernible in any way upon the tread surface of the outsole.

With this object in view the invention, in one aspect, provides an improvement in methods of making shoes which consists in cutting marginal channels forming outer and inner channel flaps, raising said flaps to open said channels, securing said outsole to the shoe by means of stitches laid in said inner channel, laying said inner channel flap to overlie and conceal said stitches, and covering that portion of said inner flap which overlies said stitches by means of said outer flap. The invention is herein illustrated in its application to the manufacture of shoes of the type wherein an insole, an upper, and an outsole are directly secured together by through-and-through stitching. After the stitching operation has been completed and the inner flap has been laid over the stitches, this flap may be rubbed or otherwise

treated to flatten out any ridges which may have been produced therein by the stitches so that after the outer flap has been laid there will be no visual indication of the presence of the stitches. If desired, such rubbing of the inner channel flap may be rendered unnecessary by providing the inner channel with a stitch-receiving groove where in the stitches will lie substantially flush with the bottom of the channel. In such instances the outer flap will entirely cover the inner flap and thus effectively cover and conceal any depressions or irregularities which may be formed in the inner flap where the latter may have been pressed into the needle holes formed by the stitching operation.

Considered in another aspect, invention is to be recognized as residing in a shoe of the type referred to comprising an outsole having outer and inner channels forming, respectively, outer and inner channel flaps, an insole, an upper having its margin interposed between the insole and the outsole, and stitches lying in said inner channel and extending through the outsole, the upper and the insole, the stitches being covered by the inner flap and the inner flap being, in turn, entirely covered by the outer flap.

In still another aspect invention is to be recognized as residing in an improved outsole for such shoes which, as herein illustrated, is provided with a marginal channel having a stitch-receiving groove formed therein, a channel flap formed by said channel and adapted to cover stitches laid in said groove, and a second channel flap formed by a marginal channel cut in the tread surface of the sole and adapted to cover entirely the first channel flap.

The invention will be explained with reference to the accompanying drawing, in which

Fig. 1 is a fragmentary cross-sectional view of a shoe sole prepared in accordance with the present invention;

Fig. 2 is a fragmentary cross-sectional view of a shoe illustrating particularly the manner in which the outer and inner channels in the outsole are opened to prepare for the stitching of the sole to the shoe;

Fig. 3 is a fragmentary cross-sectional view of the completed shoe; and

Fig. 4 is a fragmentary cross-sectional view of a sole illustrating an alternative formation of the channels and channel flaps.

In preparing a sole, such as the outsole 8, in accordance with my invention, as herein illustrated, the outsole is channeled to provide therein an outer or upper marginal channel 10 and an

- inner or lower channel 12, the channel 10 forming an outer or upper channel flap 14 and the channel 12 forming an inner or lower channel flap 16. The outer channel 10 may be conveniently formed by cutting inwardly and downwardly from the grain or tread surface of the outsole near the edge of the sole, while the inner channel 12 is cut in the bottom of the outer channel, the inner channel sloping transversely downward and outward with respect to the outer channel. As illustrated in Fig. 1, the inner channel 12 is formed with a stitch-receiving groove 18 adapted to receive the outsole-attaching stitches in substantially flush relation to the bottom surface of the channel. In cases where it is desired to reduce the thickness of the sole edge that result may advantageously be attained by beveling the sole along the marginal portion of its attaching surface as indicated at 20.
- 20 Alternatively, as shown in Fig. 4, the outer channel and the outer flap may be formed by means of a slit 100 cut in the edge of the sole while the inner channel may be so formed that it will slope transversely downward and inward with respect to the slit 100, as shown at 140. A stitch-receiving groove need not necessarily be provided in the inner channel and no such groove has been provided in the construction shown in Fig. 4.
- 30 After having been prepared as shown in Fig. 1 or Fig. 4 the outsole is laid and preliminarily secured in place upon the bottom of a shoe in a customary manner. As shown in Figs. 2 and 3, a shoe adapted to receive the outsole 8 may comprise an insole 22 and upper materials 24 the margins of which have been secured in overlasted relation to the insole by means of lasting fastenings, such as the staples 26.
- Before the outsole is permanently secured by 40 stitches to the shoe the outer and inner channels 10 and 12 must be opened by raising the outer and inner flaps 14 and 16. Advantageously these flaps may be raised into upstanding positions substantially as indicated in Fig. 2 by the 45 action of a suitably constructed flap-raising member or plow which may be provided for that purpose in a sole sewing machine of the type adapted to secure a sole to a shoe by means of through-and-through stitches, the glow being arranged 50 to open the channels in advance of the sewing instrumentalities. The outsole is herein shown as being attached to the shoe by means of lock stitches 30 which are received in the groove 18 in the inner channel 10 and extend through 55 the overlasted margins of the upper materials 24 and through the insole 22. Such sewing of the outsole may be accomplished by means of a sewing machine of the type disclosed, for example, in United States Letters Patent No. 1,827,321, granted October 13, 1931, upon application of B. T. Leveque. It should be understood, however, that if desired chain stitches may be employed instead of lock stitches for attaching the sole to the shoe. Because of the fact that the margin 60 of the outsole has been reduced or beveled upon its attaching side the stitches will draw the sole margin against the upper so that a desired tight or close edge effect will be produced all the way around the shoe.
- 70 At the completion of the outsole-stitching operation the inner channel flap 16 will be laid to cover the stitches, as shown in Fig. 3, a suitable cement having preferably been first applied within the channel 12 for the purpose of securing the flap 16 in place. If ridges or irregularities appear 75 on the outer surface of the flap 16 after the latter has been laid the flap may be subjected to a rubbing or buffing operation for the purpose of smoothing out or leveling these ridges or irregularities. Thereafter, the outer channel flap 14 over the inner flap 16 is laid and preferably is secured in place by means of cement applied within the outer channel 10. Such ridges or irregularities as may be present in the inner flap 16 and any marks such as may have been produced thereon by the rubbing or buffing operation will, of course, be entirely covered and concealed by the outer flap. If, as shown in Fig. 1, a stitch-receiving groove has been provided within the inner channel, there may be no such ridges or irregularities in the flap 16 as could be effectively removed by performing a rubbing or buffing operation thereon and in such a case, of course, no such operation will be necessary. In such a case, however, the outer flap will serve to cover and conceal any such depressions as may have been formed in the inner flap above the needle holes as a result of the pressure applied to the inner flap while it was being laid or while the shoe was being leveled. The sole-attaching stitches being covered and protected by both inner and outer channel flaps, it will be evident that even if the outer flap becomes entirely worn away as the shoe is worn the stitches will still be covered and protected from wear by the inner flap.
- Having described my invention, what I claim as new and desire to secure by Letters Patent of the United States is:
1. That improvement in methods of making shoes which consists in cutting outer and inner marginal channels in an outsole thereby forming outer and inner channel flaps, raising said flaps to open said channels, securing said outsole to a shoe by means of stitches laid in said inner channel, laying said inner channel flap to overlie said stitches, and covering that portion of said inner flap which overlies said stitches by means of said outer flap.
  2. That improvement in the art of making shoes of the type wherein an insole, an upper, and an outsole are directly secured together by through-and-through stitching which consists in fitting an outsole to provide therein a stitch-receiving channel having inner and outer channel flaps, laying the outsole upon a lasted shoe and thereafter raising said flaps to open said channel, removing the last, securing said outsole to the upper and the insole of the shoe by means of stitches laid in said channel, covering said stitches by means of said inner flap, and thereafter covering said inner flap completely by means of said outer flap.
  3. That improvement in the art of making shoes of the type wherein an insole, an upper, and an outsole are directly secured together by through-and-through stitching which consists in fitting an outsole to provide therein a stitch-receiving channel having inner and outer channel flaps, raising said flaps to open said channel, securing said outsole to the upper and the insole of the shoe by means of stitches laid in said channel, laying said inner flap to cover said stitches, rubbing said flap to smooth out any ridges produced therein by said stitches, and entirely covering said inner flap by means of said outer flap.
  4. A shoe comprising an outsole having outer and inner channels forming, respectively, outer and inner channel flaps, an insole, an upper having its margin interposed between the insole and

the outsole, and through-and-through stitches lying in said inner channel and extending through the outsole, the upper and the insole, said stitches being covered by said inner flap and said inner flap being, in turn, entirely covered by said outer flap.

5. A shoe comprising an insole, an upper having its margin disposed in overlasted relation to the insole, an outsole having a marginal stitch-receiving channel and inner and outer channel flaps, the margin of the outsole being reduced at its attaching side, and outsole-attaching stitches received in said channel and extending through the overlasted upper margin and through 10 the insole, said stitches being covered by said inner flap and said inner flap being covered entirely by said outer flap.

6. A shoe comprising an insole, an upper having its margin disposed in overlasted relation to the insole, an outsole having a peripherally-extending channel forming an outer channel flap, a second peripherally-extending channel sloping transversely inwardly and away from said first channel and forming an inner channel flap, and 20 25 outsole-attaching stitches received in said second channel and extending through the overlasted upper margin and through the insole, the portions of said stitches which lie in said channel being covered by said inner flap and said inner flap, in turn, covered by said outer flap.

7. A shoe comprising an insole, an upper, an outsole provided with outer and inner channels forming, respectively, outer and inner channel flaps adjacent to the tread surface of the sole, and outsole-attaching stitches received in said 30 35 inner channel and extending substantially perpendicular to the tread surface of the outsole, said stitches being covered by said inner flap and

said inner flap being entirely covered by said outer flap.

8. An outsole for a shoe of the type wherein an insole, an upper, and an outsole are directly secured together by through-and-through stitching, said outsole having an outer marginal channel cut in the tread surface of the sole and forming an outer channel flap, and a stitch-receiving channel cut in the inner side of said outer channel and forming an inner channel flap adapted 10 to cover stitches laid in said inner channel and to be, in turn, covered by said outer channel flap.

9. An outsole provided with a marginal channel having a stitch-receiving groove, a channel 15 flap for covering stitches laid in said groove, and a second channel flap constructed and arranged to cover entirely the first channel flap.

10. An outsole for a shoe of the type wherein an insole, an upper, and an outsole are directly 20 secured together by through-and-through stitching having a peripherally-extending stitch-receiving channel forming an inner channel flap adapted to cover stitches received in said channel, and a second peripherally-extending channel 25 forming an outer flap at the tread side of the sole adapted to cover entirely said inner flap, said outsole having its edge reduced in thickness only at its attaching side.

11. A shoe sole having a peripherally-extending 30 channel forming an outer channel flap, and a second peripherally-extending channel sloping transversely inwardly and away from said first channel and forming an inner channel flap adapted 35 to cover stitches laid in said second channel and to be, in turn, covered entirely by said outer flap.
